HAIR REMOVING DEVICE

Hugo Wurfschmit, New York, N. Y., assignor of
one-half to Carl E. Carlsen, New York, N. Y.

Application November 12, 1947, Serial No. 785,374

2 Claims. (Cl. 51—187)

1

This invention relates to a hair removing device which would be useful especially for women in removing undesirable hair, such as from legs and arms, and under the arm pit. The device may in like manner be applied to remove soft hair from the face, and may in this connection be used by young men who experience their first growth of a soft beard.

It is, of course, well known that in applying any hair remover of this kind, the skin must be dry, especially in hot or sticky weather.

The device with its abrasive material is applied to the skin by using circular strokes, alternating from left to right and right to left.

The present device is formed with a number of abrasive layers, provided with sharp edged apertures or holes therein.

As the device presents a uniform surface all over, it may be applied with equally good results to any part of the surface of the skin. It may in this connection be stated that the present device thus possesses a great advantage over some glove-like air remover where the unevenness of the abrading surface, due to the shape of the fingers prevents an equal application of the device to all parts of the skin.

The present device however, is provided with smoothly rounded curves, so as to effectively engage any part of the surface of the body.

With the above and other objects in view, this invention consists of the novel features of construction, combination and arrangement of parts, hereinafter fully described, claimed and illustrated in the accompanying drawings forming part of this application, and in which similar characters of reference indicate corresponding parts in all views, and in which:

Figure 1 is a somewhat perspective elevational view of my device.

Figure 2 is a section taken on the line 2—2 in Figure 1.

Figure 3 is a section taken on the line 3—3 in Figure 1.

Figure 4 is a side elevational view, showing a slight modification of my device.

Figure 5 is a side elevational view, showing a detail construction of part of the device, and

Figure 6 shows an end view of the device with the pin removed.

Referring more particularly to the drawing, the numeral 10 indicates a piece of comparatively soft material, which will permit the insertion therein of a pin or nail-like plug 11 by only applying a slight pressure to the latter, thus said material may be soft wood, cardboard, or the like.

2

A number of layers of abrasive material, such as paper 12 provided with an abrasive surface upon one side thereof, are arranged around the member 10. Said paper, the kind of which is well known, has a thickness heavier than ordinary writing paper, and this paper, which when unwound would appear as a long strip, is provided with holes 13 therein; said holes are cut out sharply, so as to impart to their edges a cutting ability for the cutting of hair, which characteristic forms an auxiliary aspect of this invention.

The said layers have their holes stamped according to a pattern, so that there will always be a specific hole in the strip of paper 12 so positioned that when the latter is wound upon the member 10, said hole 14, will be at one end of the device, as shown in dotted line in Figure 1, to accommodate the pin 11, or in other words said holes 14 will lie one above the other, when the layers are wound on the member 10.

The layers of the paper 12 are also provided with perforations 16 so that a layer, when worn, may easily be torn off, even without loosening the pin 11, or by withdrawing the latter slightly.

25 To facilitate said tearing off a small slit 23 is made at the end of the layers, said slit extending to the hole 14, as shown in Figure 6.

Between the layers of the paper 12 may be positioned thin layers of tissue paper 17 to protect the abrading surfaces of the respective layers.

30 However, if desired, the layers may be wound one upon the other without any tissue paper between them; in this case it is, however, desirable to arrange a soft layer of suitable material 18 between the member 10 and the innermost layer of the paper 12, as shown in Figure 4.

In Figure 5 is shown how two corrugated layers of paper 20, 20 may take the place of the soft material 18, shown in Figure 4.

35 Said corrugated layers 20, 20 are placed reversely over the member 10, and so that there is only one single corrugated layer at the ends of the member 10.

The said material 18 or corrugated layers 20, 20 may also be retained, if desired, even if the layers of paper 12 are provided with tissue paper therebetween.

40 The pin 11 may, if desired, have the shape of an elongated headed pin of the well known type, as shown at 15. When a layer of paper is torn off, the pin 11 is progressively pushed in a little farther in the member 10.

45 The said corrugated layer or layers may also just be wound upon the member 10, without being

reversely positioned; and while the abrasive layers have herein been described with holes, the latter may, if desired, be omitted.

It should be noted that the ends of my device are rounded with smooth curves for the purpose hereinbefore set forth.

What I claim as new, and desire to secure by Letters Patent of the United States, is:

1. A hair removing device comprising a substantially rectangular base of semi-soft material, a strip of paper-like material having an abrasive surface upon one side thereof and adapted to be wound a number of times around said base longitudinally, layers of soft material inserted among the layers of said strip, said strip being formed with a plurality of sharply edged holes, the superposed layers of said strip being at one end of the base provided with a plurality of perforations therein, whereby to progressively permit detachment of a layer of said strip, each of said latter layers being at said end formed with a hole in the center thereof, and a headed pin adapted to engage said hole and become embedded in said base, the latter layers being at said end formed

with a slit leading from the perforations to said hole, whereby always to facilitate the removal of the outermost layer of the strip.

2. In a device, as claimed in claim 1, and wherein corrugated sheets of paper may be disposed between the innermost layer of the strip and the base.

HUGO WURFSCHMIT.
